UNITED STATES PATENT OFFICE.

LILY H. COWAN, OF DURHAM, NORTH CAROLINA.

INVALID KNEE-REST.

No. 830,416.

Specification of Letters Patent.

Patented Sept. 4, 1906.

Application filed March 17, 1906. Serial No. 306,610.

To all whom it may concern:

Be it known that I, LILY H. COWAN, a citizen of the United States, residing at Durham, in the county of Durham and State of North Carolina, have invented new and useful Improvements in Invalid Knee-Rests, of which the following is a specification.

This invention relates to invalid knee-rests, the object of the invention being to provide a knee-rest especially adapted to the requirements of surgeons, nurses, and physicians in hospitals and at other places, the improved knee-rest being adapted to be placed upon the bed to support the knees and lower portion of the body to relieve patient's position after operation, the device also embodying means for supporting bedclothes and holding the foot or feet of the patient at the necessary elevation to prevent hemorrhage after amputation, &c.

With the above and other objects in view the nature of which will more fully appear as the description proceeds, the invention consists in the novel construction and combination of parts hereinafter more fully described, illustrated, and claimed.

In the accompanying drawings, Figure 1 is a side elevation of the knee-rest, showing one method of using the same. Fig. 2 is a plan view thereof. Fig. 3 is an enlarged side elevation of the knee-rest shown used as a prop for the patient's back. Fig. 4 is an enlarged fragmentary side elevation showing the connection between the hinged members or sections of the rest. Fig. 5 is a detail section showing interchangeable supporting-legs and the manner of connecting the same to the body of the rest.

The knee-rest contemplated in this invention comprises an oblong frame composed of two sections, an upper section 1 and a lower section 2, the said sections being of suitable length and connected together at their meeting ends by hinges 3. The lower section 2 consists of an open rectangular frame over which is stretched a covering 4 of woven fabric, such as cane-seating, while the upper section 1 has one portion thereof provided with a covering 5, the end portion of the section 1 being left open for a purpose which will hereinafter appear. The sections 1 and 2 are further connected by means of braces 6, arranged at opposite sides thereof and pivotally connected to one of the sections, as shown at 7, the opposite ends of the braces 6 being slotted, as shown at 8, and provided

with notches or teeth 9, adapted to engage pins or projections 10 on the other section of the knee-rest, whereby the two sections of the knee-rest may be held at any desired angle with relation to each other, as clearly shown in Figs. 1, 3, and 4. Connected pivotally to the farther end of the section 2 is a bail-shaped frame 11, embodying the arms 12, the end cross-bar 13, and provided with one or more intermediate cross-bars 14. If desired, however, the cross-bars 14 may be omitted. Said frame 11 is pivotally connected to the section 2 of the knee-rest at the points 15, so that it may be swung to stand either vertically, as shown in Fig. 1, or folded down flatwise against the section 2, as shown in Fig. 2. This adjustable frame 11 is adapted to support the bedclothes at an elevation, so as to relieve the feet of the patient from the weight of the covering in case either foot is injured. The outer corners of the section 2 of the knee-rest are also provided with threaded sockets 16, adapted to receive the reduced and threaded ends 17 of one or more sets of interchangeable supporting-legs 18 of different lengths, whereby the frame-section 2 may be supported at any desired elevation above the bed or other surface upon which the device is placed.

By reference to Fig. 1 the method of using the knee-rest will be seen, and it will be observed that the feet of the patient are held at a suitable elevation to prevent hemorrhage in case of amputation, and any desired elevation may be obtained by employing supporting-legs of suitable length. The construction of the upper section 1 of the frame also adapts suitable appliances to be placed under the patient while lying within the bed and without removal therefrom, thus greatly facilitating the handling of the patient.

I claim—

1. A knee-rest embodying a plurality of sections having a jointed connection with each other, braces for adjusting and maintaining the angle between the sections, and detachable legs for supporting one of the sections at a suitable elevation.
2. A knee-rest embodying hinged sections, means for adjusting said sections at an angle to each other and maintaining such angle, and a bedclothes-supporting frame having a jointed connection with one of said sections and adapted to be positioned at any angle with respect to said section.
3. A knee-rest embodying hinged sections,

pins on one section, and braces pivotally connected to the adjoining section and provided with notches or shoulders adapted to engage the said pins and hold the sections at the desired angle to each other, substantially as described.

4. A knee-rest embodying hinge sections, means for adjusting the angle of said sections and maintaining said angle, and interchange-

able supporting-legs of different lengths applicable to one of the sections, substantially as described. 10

In testimony whereof I affix my signature in presence of two witnesses.

LILY H. COWAN.
